UNITED STATES PATENT OFFICE.

ERNEST L. CONDON, OF MEDWAY, MASSACHUSETTS, ASSIGNOR TO UNITED SODA FOUNTAIN COMPANY, OF BOSTON, MASSACHUSETTS, A CORPORATION OF MASSACHUSETTS.

DETACHABLE-COVER CONSTRUCTION.

1,415,149.

Specification of Letters Patent. Patented May 9, 1922.

Application filed January 5, 1920. Serial No. 349,460.

To all whom it may concern:

Be it known that I, ERNEST L. CONDON, a citizen of the United States, and resident of Medway, in the county of Norfolk and State 5 of Massachusetts, have invented new and useful Improvements in Detachable-Cover Constructions, of which the following is a specification.

This invention relates to a receptacle top 10 and detachable cover therefor, and while applicable to receptacles generally it is particularly designed for an ice box or chest of the kind used at soda fountains for storing cans of ice cream conveniently for service.

15 In the accompanying drawings which illustrate a preferred embodiment of the invention—

Fig. 1 is a plan view of the cover and receptacle top;

20 Fig. 2 is a section on line 2—2 of Fig. 1;

Fig. 3 is a plan view of the receptacle top and associated parts with cover removed; and

25 Fig. 4 is a plan view of the cover.

The top wall of the ice box or other receptacle 5 is made with a curvilinear and preferably a circular opening into which is set a ring or flange 6 bordering the opening and projecting a little above the plane of the top 30 wall. 7 is a segment shaped plate of sheet metal made with a straight edge, and permanently secured to the top of the flange 6. 8 is a removable cover covering the part of the opening not covered by plate 7, also made 35 of sheet metal and provided if desired with a lining 9 of heat insulating material. The cover 8 rests when closed on top of the flange 6 and conforms to the shape of the opening with its straight edge adjacent to the straight 40 edge of plate 7.

The cover 8 swings on its straight edge as a pivot and is in no way attached to the receptacle top. Two ledges 10, 10, made of sheet metal are secured to the under side of plate 7 inside of and adjacent to ring 6. The top surfaces of ledges 10 are in the same plane with the top of ring 6 and afford a broad bearing surface for the hinge edge of the cover which would otherwise wear and become worn by the relatively sharp edge of the ring 6, if the straight edge of the cover worked merely on the ring 6.

The cover 8 has a tongue or projection 11 secured to its under side and extending from

the straight edge between the ledges 10, 10, 55 and under the plate 7 when the cover is closed. This tongue serves to guide and hold the cover in proper position on the receptacle top.

A rod 12 is fixed at its ends to the inner sides of the ring 6 and extends across the opening a little below and in front of the straight edge of plate 7. The rod 12 constitutes a stop to engage the tongue 11 and hold the cover in open, upstanding position as indicated in dotted lines in Fig. 2, when the cover is swung open.

Below the rod and underneath the tongue 11 when in open position, is a trough or gutter 13 which catches and carries away any 70 moisture which drips from the tongue 11, when the cover is opened, or from the ledges 10. The tongue 11 extends under the plate 7 and closes the crack or joint between the straight edge of plate 7 and the straight edge 75 of the cover when the latter is closed.

The cover may be removed for cleaning the parts by merely opening it and slipping the tongue vertically out from between the ledges 10. Similarly it may be replaced by 80 inserting the tongue between the ledges 10 which guide it into correct working position.

It will be understood that the ice cream can is set into the receptacle below the opening and cover, and while readily accessible for 85 service is fully protected by the cover, when closed, and safeguarded against any water or other moisture dripping into the can from the top of the chest by the flange 6, and by the trough 13, which catches and carries 90 away moisture which might otherwise drip through the opening when the cover is opened.

I claim:

1. In combination, a receptacle top having an opening, a freely removable cover for the opening adapted to swing on one edge as a hinge, ledges adapted to engage and support the hinge edge of the cover throughout its swinging movement, and means to position the cover over the opening. 95

2. In combination, a receptacle top having an opening, a flange extending above said opening, a freely removable cover for the 105 opening adapted to swing on one edge as a hinge, ledges adapted to engage and support the hinge edge of the cover throughout its

swinging movement, and means to position the cover over the opening.

3. In combination a receptacle top having an opening, a flange extending above said opening, a freely removable cover for the opening adapted to swing on one edge as a hinge, ledges disposed in a plane coincident with the top of the flange to engage the hinge edge of the cover, and means to position the cover on the flange.

4. In combination a receptacle top having an opening, a flange extending above said opening, a freely removable cover for the opening adapted to swing on one edge as a hinge, a pair of ledges inside of and adjacent to the flange and disposed in a plane coincident with the top of the flange to engage the hinge edge of the cover, and means interposed between said ledges to position the cover on the flange.

5. In combination a receptacle top having an opening, a flange extending above said opening, a removable segmental cover for the opening adapted to swing on one edge as a hinge, a pair of ledges inside of and adjacent to the flange and disposed in a plane coincident with the top of the flange to engage the hinge edge of the cover, and a tongue extending from the hinge edge of the cover and normally extending between said ledges.

6. In combination, a receptacle top having an opening, a flange bordering said opening, a rod fixed within the flange and extending across the opening, a removable cover adapted to swing on one edge as a hinge and normally resting upon the upper edge of said flange, and a tongue on the cover adapted to engage the rod and hold the cover in open position.

7. In combination, a receptacle top having an opening, a flange bordering said opening, a plate fixed to the top of the flange and covering part of the opening, a rod fixed within the flange and extending across the opening and below said plate, a removable cover adapted to swing on one edge as a hinge, and a tongue on the cover adapted to extend under the plate when the cover is closed and to engage the rod and support the cover when the latter is opened.

8. In combination a receptacle top having an opening, a freely removable cover for the opening adapted to swing on one edge as a hinge, said cover having a rearwardly extending tongue, and a trough underneath the hinge edge of the cover adapted to carry off moisture which may pass through the hinge joint and drip from said tongue.

9. In combination, a receptacle top having an opening, a flange bordering said opening, a plate fixed to the top of the flange and covering a part of the opening, a removable cover for covering the rest of the

opening adapted to swing on one edge as a hinge, said cover having a tongue normally extending under the plate when the cover is closed and a trough extending across the opening underneath the joint between the cover and plate and positioned to underlie the lower edge of said tongue when the cover is opened.

10. In combination, a receptacle top having a curvilinear opening, a flange bordering and extending above said opening, a segmental plate fixed to the top of the flange and covering part of the opening, a removable cover for covering the rest of the opening adapted to swing on its edge adjoining the straight edge of the segmental plate, a tongue on said cover extending under the segmental plate when the cover is closed, and a rod fixed within the flange and extending across the opening adapted to engage the tongue and support the cover in open position.

11. In combination, a receptacle top having a curvilinear opening, a flange bordering and extending above said opening, a segmental plate fixed to the top of the flange and covering part of the opening, a pair of ledges inside of and adjacent to the flange and disposed in a plane coincident with the top of the flange, a removable cover for covering the rest of the opening adapted to swing on its edge engaging said ledges adjacent the straight edge of the segmental plate, a tongue on said cover extending between said ledges and under the segmental plate when the cover is closed, and a rod fixed within the flange and extending across the opening adapted to engage the tongue and support the cover in open position.

12. A device of the class described comprising a circular flange, a segmental plate permanently secured to the edge thereof, a bar extending across said flange substantially below the straight edge of said plate and spaced therefrom, a segmental cover member having its straight edge abutting the straight edge of said plate, a tongue member extending from the straight edge of said cover member and into the space between said plate and bar, and heat insulating means upon the under side of said cover member.

13. A receptacle top having an opening, a removable cover for the opening adapted to swing on one edge as a hinge, ledges constructed and arranged to engage and support the hinge edge of the cover and a single centrally disposed tongue forming an extension of said cover and serving to position said cover relative to said ledges throughout its swinging movement.

Signed by me at Boston, Massachusetts, this 30 day of December, 1919.

ERNEST L. CONDON.
